UNITED STATES PATENT OFFICE

AUGUST H. LEIPERT, OF COLLEGE POINT, NEW YORK, ASSIGNOR TO INTERNATIONAL MOTOR COMPANY, OF NEW YORK, N. Y., A CORPORATION OF DELAWARE

VALVE SEAT

Original application filed January 31, 1928, Serial No. 250,941. Divided and this application filed January 11, 1929. Serial No. 331,827.

The present application is the division of applicant's application Ser. No. 250,941, filed January 31, 1928.

In an endeavor to carry off the heat from the valves of internal combustion engines more rapidly, it has been proposed to form the valve seat of a material having greater heat conductivity than the engine casting.

To do this, the valve seat has been formed in several ways, for example, cast either with or after the casting of the main cylinder blocks, or fastened into place after the casting and machining operations have been completed.

The present invention resides in providing an improved valve seat in situ in which the material is expanded and rolled into place. It is also contemplated to form the valve contacting portions of the valve seat of greater density than the portion remote from the valve and adjacent the cylinder casting, whereby the life of the seat will be increased and the heat from the valve carried off more rapidly. The seat as thus constructed, has essentially a homogeneous union of the metal thereof with the metal of the casting, thereby further insuring the most favorable conditions for heat conduction.

Further objects and advantages of the invention will appear as the description proceeds and reference will now be had to the accompanying drawings, wherein:

Figure 1 is a view in section taken on line 1-1 of Figure 4, but showing the valve seat before being rolled into position.

Figure 2 is a segmental view on the same section line as Figure 1, but showing the valve seat rolled into position so that it engages the underhooking edge of the casting.

Figure 3 is a view similar to Figure 2, showing the valve seat after it has been rolled into the proper form.

Figure 4 is a plan view showing the valve seat after it has been rolled and formed.

Figure 5 is a segmental view in section taken on line 5-5 of Figure 4.

Figure 6 is a view in section, similar to Figure 1, but showing the valve engaging the finished valve seat.

Referring particularly to the above described figures, *a* designates the cylinder cast-

ing of an engine provided with a valve hole *a'*. The retaining wall of the cylinder is undercut as at *a''* to provide a groove into which the material of the valve seat is rolled. This under-cut portion forms a shoulder which prevents the valve seat from being removed and receives the latter when it is installed in the following manner.

The valve seat *b*, which may be of annular form, is placed as shown in Figure 1. A suitable expanded *c* of well known construction is placed within the valve seat and the latter is rolled and expanded into the under-cut portion *a''* of the cylinder wall *a*. During this rolling operation, the material of the valve seat becomes denser. That portion of the seat adjacent the valve will be of relatively greater density than the portion of the seat adjacent the underhooking edge. This is true also in the next step of rolling the taper in the valve seat after it has been forced into the position shown in Figure 2. Figure 3 illustrates the valve seat with the tapering valve engageable surface formed therein. By forming the seat adjacent the taper with a very compressed and close-grained structure, its life is greatly increased as well as its ability to carry off the heat rapidly.

In order that the seat may be prevented from turning, serrations or recesses *a''* are formed in the wall of the cavity receiving the seat and in the rolling of the seat into position, the material of the seat will be forced into the recesses to serve as a key to prevent the turning thereof. This is illustrated in Figures 4 and 5, wherein recesses *a''* are formed in the casting *a* and receive the rolled portions *b'* of the seat when it is rolled into position. Of course, the particular form of staking or means for securing the seat against rotation, is immaterial since any well known provision of this character may be utilized.

The metal constituting the valve seat may be of any composition capable of being expanded or rolled and transferring heat better than cast metal. A copper aluminum bronze alloy, being homogeneous and not flaking, has been found to be satisfactory metal for these valve seats. The particular means formed on the cylinder casting for re-

taining the valve seat in position is immaterial, since shoulders and projections of many forms may be substituted for the underhooked groove to receive and engage the expanded seat material.

5 In practice it has been found that the metal of the seat, in being rolled, tends to be turned back at the upper edge and to be pulled away from the rim of the horizontal portion of the groove. To reduce this action an expander is used having rollers, the outer surfaces of which always lie in planes parallel to the axis of the expander. In fact it is sometimes necessary to secure a plate *d* to the block to 10 confine the metal of the seat in its proper position and cause it to engage the horizontal portion of the groove intimately.

15 Although the invention has been described with specific reference to the accompanying drawings, no limitation as to structure or means of applying the seat is to be placed upon it, save as defined in the appended claims.

What I claim is:

20 25 1. A valve seat construction comprising a cylinder casting formed with a groove and having a recess in the wall of the groove, and a valve seat in the groove having a greater density adjacent its valve contacting area than its density elsewhere, said valve seat engag- 30 ing in said recess.

35 2. A valve seat construction comprising a cylinder casting formed with an undercut groove and having recesses in the wall of the groove, a valve seat in the groove having a greater density adjacent the valve contacting portion than elsewhere, and portions on the seat extending in said recesses.

40 This specification signed this 28th day of December A. D. 1928.

AUGUST H. LEIPERT.
